INVENTOR

WITNESS: *J. T. L. Wright*

BY *Victor J. Evans*

ATTORNEY

UNITED STATES PATENT OFFICE.

LAUREL L. CLARK, OF CRAWFORDSVILLE, INDIANA.

HUMIDOR.

Application filed August 8, 1925. Serial No. 48,135.

This invention relates to improvements in cigar containers, the general object being for retaining moisture and conserving the essential qualities of tobacco as contained in 5 cigars at the time they were packed, ready for consumption by the manufacturer; also as a protector against the damaging effects of atmospheric changes, heated stores, strong 10 daylight, and damp storage places as is the case where cigars are displayed in show 15 cases and windows, and stored in cellars; moreover cigars maintained at an even degree of humidity under any and all conditions, will prevent throat irritation caused by drawing into the throat while lighting 20 dry cigars, fine soil and tobacco dust that adhere to all tobacco leaves until consumed.

Another object of my invention is the provision of means for adding moisture when 25 needed by a device within the top of the container, which, in its normal upright position allowing the natural precipitation of moisture thus contained within the top of said container, to be used as required for keeping 30 contents of said container in proper salable condition.

With the above and other objects in view the invention further includes the following novel features and details of construction, to be hereinafter more fully described, 35 illustrated in the accompanying drawings and pointed out in the appended claims:

In the drawings:—

Figure 1 is a vertical sectional view taken 40 through my invention when assembled.

Figure 2 is a transverse section taken on line 2—2 of Figure 1.

Figure 3 is a bottom plan view of the 45 removable cover lid and illustrating the absorbent means thereon.

Figure 4 is a fragmentary elevation of the container and showing the relative arrangement and support of the absorbent means within the lid therefor.

Figure 5 is a similar view of the receptacle 50 and illustrating the contents thereof.

Referring to the drawings in detail, wherein like characters of reference denote corresponding parts, the reference character 55 10 indicates a container having the conventional form of removable cover cap 11 therefor, and which may be constructed of any sheet metal of suitable thickness and temper, all of the above is of the usual and well known construction and forms no part of the

present application for letters patent but is merely shown for purposes of illustration in bringing forward the novel advantages of the above entitled invention.

Positioned within the said container 10 is 60 a cylindrical receptacle 12 within which cigars are placed, and which must contain a certain number of cigars to constitute a statutory package of cigars as required by the United States Internal Revenue regulations; 65 contents of said statutory package when placed into the container 10 for final disposal will contain the desired degree of moisture and be hermetically sealed, and to remain sealed until the cigars therein are 70 exposed for sale in a retail way, after which a cover or top 13 of the receptacle 12 is removed and to remain off until the cigars therein are sold, in the meantime the moisture device having been serving its purpose 75 by supplying moist air throughout an air space 13' between the corresponding sides of the container 10 and receptacle 12 whenever the condition of the cigars require added moisture. The trade being served direct 80 from the container in its assembled form, subjects its contents to exposure only while cigars are being withdrawn therefrom. The scientific principle involved in maintaining an even degree moisture in the contents of 85 the receptacle 12 while enclosed in the container 10 is made clear by considering the construction of and materials comprising the above entitled invention.

Arranged beneath the cover 11 is a disk 90 14 which is preferably constructed of absorbent material adapted to be saturated with water or the like. The disk is arranged directly above the tray 16 which is provided with raised portions 17 upon which the disk 95 reposes, the raised portions of course supporting the disk in spaced relation to the tray. The tray is provided with openings 15 as shown, whereby moisture from the disk is admitted into the container.

It will thus be noted from the foregoing description and accompanying drawings that owing to the respective configurations and diameters of the container 10 and receptacle 12 that the latter may be readily and easily placed within the former and allowing and creating the air space 13', as mentioned in the foregoing, of suitable dimensions which completely envelops the receptacle 12 when filled with cigars of a desired 110

degree of moisture, is hermetically sealed and placed into the container 10 on to which is placed the removable cover cap 11 within which the moistening means is bonded; a few drops of water supplied to the cedar disk 14 will cause the air space 13' to be filled with moist air, arresting the evaporation of the sealed in moisture permeating the contents of the receptacle 12; thus serving and preserving the essential qualities of cigars or other tobacco products indefinitely.

It is further to be noted that this invention will prove equally and effectually as well when used in preserving both smoking and chewing tobacco.

The invention is susceptible of various changes in its form, proportions and minor details of construction, and the right is herein reserved to make such changes as properly fall within the scope of the appended claims.

Having described my invention what is claimed is:—

In a humidor, a casing, a receptacle arranged within the casing and spaced from the wall thereof, said casing projecting an appreciable distance above the receptacle, a perforated tray including an annular flange reposing upon the upper edge of the casing and supporting the tray within the latter in close proximity to said receptacle, raised portions formed on the bottom of said tray and arranged at diametrically opposite points, a disk of absorbent material reposing on said raised portions and supported within the tray in spaced relation to the bottom thereof, and a cover for said casing, said cover reposing upon said flange to assist in holding the tray associated with the casing.

In testimony whereof I affix my signature.

LAUREL L. CLARK.
